FOOTBALL GAME DEVICE

Joseph J. Warren, Cleveland, Ohio

Application January 31, 1946, Serial No. 644,568

1 Claim. (Cl. 273—94)

1

My invention relates to a football game and relates more particularly to a football game adapted to be played upon a playing board, and a ball adapted to be catapulted over such board and adapted to come to rest in prescribed spaces upon such board.

It particularly relates to an improvement in the football game shown in my Letters Patent No. 1,922,904. In the game shown in the aforementioned patent, a ball propelling mechanism 20 is movable over the board and forms the offensive team. Plays are executed by placing a ball in the ball propelling mechanism and projecting the ball therefrom onto the playing field. Interception of the plays of the offensive team are effected by a defensive team composed of characters which are slideably mounted upon a frame disposed transversely of the playing field.

It is an object of my present invention to provide an improvement over the football game covered by the aforesaid Letters Patent wherein the ball propelling mechanism may be securely affixed to the board and not interfere with the playing field area, and improved mechanism may be provided for realistically effecting passes and kicks.

A further object of my invention is to provide an improved football game which will be simple in operation, composed of but relatively few moving parts, inexpensive in manufacture, and most effective in use.

Another object of my invention is to provide an improved football game wherein ample scope is provided for the simulation of the actual playing tactics of a regulation football game with virtually all of the gains, penalties, chance and skill involved therein.

Other objects of my invention and the invention itself will hereinafter become more apparent to those skilled in the particular art to which my invention appertains by reference to the following description and drawings accompanying the same, in which drawings:

Fig. 1 is a top plan view of a game board constructed in accordance with a preferred embodiment of my invention;

Fig. 2 is an enlarged sectional view taken on the line 2—2 of Fig. 1;

Fig. 3 is a sectional view taken on the line 3—3 of Fig. 1;

Fig. 4 is an enlarged sectional view of the mounting for the hinged platform of Fig. 1, the view being partially broken away to show the same more clearly;

2

Fig. 5 is a sectional view taken on the line 5—5 of Fig. 1.

Referring now to the drawings, in all of which like parts are designated by like reference characters, 10 designates the playing board which is laid out as a miniature football field having longitudinally extending lines 11—11' which form the side lines of the playing field and transversely extending lines 12 which form the five yard markers of the field. At the left hand sides of the lines 12, the numerals "5," "10," "15," "20," "25," "30," "35," "40," etc., appear. At the end zone 13, the board is elevated, as best shown in Fig. 2, and thus an incline is provided which a ball or marker 14, interposed in a longitudinally extending raceway 15 disposed at the right hand side of the playing field, is adapted to traverse.

The ball 14, as shown in Fig. 1, is spring-propelled, the said spring 16 being telescoped over a plunger 17 and seating upon an enlarged head 18 thereof and against the raised outer edge 19 of the board. Said plunger is provided with a handle 20 and when the handle is manually retracted and then released, the stem is reciprocably movable within the end portion of the raceway 15 and exerts a projectile force to the ball 14 causing the same to traverse the raceway 15 and ascend the incline. When the ball reaches the upper portion of the incline, a deflector 21 formed by a narrow metallic band secured at one end to the outer rim of the incline, as at 22, and slightly bent at its free end 23, prevents the ball from simply following the edge of the incline and deflects the same onto the playing field.

Transversely of the said field and preferably integrally joined to the inclined surface 13, as best shown in Fig. 2, a preferably concavely formed playing surface 24 is provided with a series of transversely aligned depressions 25. Adjacent the right hand edge of said surface 24, a second deflector means 26 is disposed adapted to act upon any ball which may come in contact therewith. The said deflector 26 is secured to the longitudinally extending upstanding side wall 11 which, together with another side wall of substantially equal length 27, joined thereto, as at "x," forms a relatively long and narrow space adapted to receive a yard measure 28 upon which the position of the playing teams is recorded at all times after each play by means of a point 29 manually operable and slideably mounted, as shown in Fig. 3, upon the wall 11.

Adjacent the playing surface 24 and disposed intermediately of the playing field, an interme-

diate centrally disposed movable portion 30 of the playing field, which is hingedly mounted upon a pair of rods 31 and 32, as shown, is adapted to be raised or lowered, as best illustrated in Fig. 2, by means of a handle 33 forming an extension of the rod 32 and bent upwardly at a 45° angle thereto.

Associated with said handle and securely mounted on the outer side of the edge 11', forming the left hand side line of the field, is a metallic clamp 34 preferably notched, as shown in Fig. 1 at 35, to form locking engagement with the handle when it is desired to tiltably raise the central portion 30 of the field to the inclined position shown in dotted lines in Fig. 2. Disposed on either side of the movable portion 30 of the field are substantially square sections S' and S in which two pair of aligned depressions are located.

The main playing section X of the field is divided into a series of zones by the yard lines 12 and each of these zones adjacent said lines are provided with a plurality of openings or depressions 60 in one of which the ball when rolled across the playing surface may come to rest.

In order to obstruct the free passage further of the ball over the section X of the playing field, characters are provided which represent the defensive team in a football game. The offensive team, it will be obvious, is represented by the ball in play.

The defensive team's characters are represented by seven front line players 36, a pair of half backs 37, backs 38, and the end players at either end of the front line players are detachably secured in slots in their forwardmost position and adapted, when desired, to be shifted to the slots 39 disposed centrally and rearwardly of the backs which presents an advantage when it is desired to block the opposing players' passes or kicks, so delivered over the inclined platform portion 30.

A pair of goal posts are preferably disposed as at "z" for accomplishing the extra point after a touchdown and a pair of similar goal posts may be positioned as at "w" for the purpose of making a field goal.

At the end of the field, the last series of circular openings 42 in the end zone are surrounded on their sides and rearmost portions by circularly notched portions 41 provided in a rectangular end plate "y". It will be noted that additional yardage indicia "45," "50," "55," "60," "65," "70," "75," "80," and "85" in the openings 42 are employed.

The various rows of depressions or openings, 60, 42, etc., in the different zones of the playing surface are staggered in relation to those of the adjacent rows to add to the skill required in the game.

Also, certain of the depressions in all rows, with the exception of the end row, are suitably inscribed with indicia such as "F," "C" and "I," to indicate the progress of the ball when the same falls in any of such marked openings. "F" indicates a fumble; and "C" and "I" represent "complete" or "incomplete" passes.

Beneath certain of the openings marked "I," a further number, such as "10," "15," "20," "25," "30," "35," "40," "45," "50," "55," occurs in such inscription indicates the return of the ball the yardage indicated thereby. A further character "O-S" is found in certain openings or depressions and signifies an "off-side" play. Also, in certain depressions on the field in the row in front of the first row of defensive players, the

numerals "5—," "10—" appear, to indicate loss of yardage on the play. Various colors might also be employed for indicating the play. It will thus be seen that all of the probabilities of actual play are provided for in my game.

In operation, the marker 29 is placed on the 40-yard line to begin the play and the hinged platform 30 is raised for the kick-off which is effected by one player placing a ball 14 in the raceway adjacent the end of the plunger, retracting the handle 20 and allowing the same to snap back against the ball by the action of the spring, the head of the plunger 17 hitting the ball with sufficient force to send the same into the inclined end zone 13, thus placing the ball in position, according to its speed, to be projected over the platform 30 and over the heads of some of the defensive players, as shown in Fig. 2, onto the playing field and into an opening or depression in one of the zones of play.

When the ball comes to rest, the zone character at the left of the yard lines indicates the length of the kick and the ball is returned to its initial position in the raceway for the second play and the hinged platform 30 lowered to a line with the remaining field.

As in actual football, the player representing the offensive team endeavors to make successive first downs and to achieve a touchdown, as recorded by "G" or goal on the measure 28 at either end thereof. Upon failure to make a "first down" the ball passes to the opposing player and is placed in motion in like manner.

In the event of an off-side play, the ball is returned to the position of the previous down, with five-yard penalty imposed.

It will be noted that my invention by means of the hinged portion 30 permits the exercise of judgment as to the proper play, whether the same be a line play as effected by lowering the platform 30 and attempting to get the ball through between the defensive players, or a pass which is effected by shooting over the raised platform, and over the heads of the first line defensive players, or kicking as on "fourth down" by raising the portion 30.

The defensive team also has a choice in its defense formation as the ends may be moved to the rearmost position 39 as hereinbefore described to aid in blocking a pass or kick.

When passing, the ball must come to rest in either an opening marked "C" or "I," and is either complete or incomplete according to its rest position.

While I have shown propelling means for catapulting the ball along a raceway, up onto the inclined end 13 against a deflector 21, it is to be understood that the ball might be projected onto the field and over the platform 30, whether level with the rest of the field or inclined with respect thereto, by any preferred means without departing from the spirit of my invention.

Other and numerous departures might further be made without departing from the spirit of my invention and the scope of the appended claim.

I claim:

A football game device of the type wherein a ball is catapulted over a playing field, comprising a playing field having a level and horizontally disposed playing surface and an inclined surface, said playing surface being divided into sections and lined to indicate yardage markers, each section having a plurality of ball receiving depressions therein some of which are provided with indicia and means hingedly secured to said play-

ing surface and adjacent the inclined surface, said means being adapted to lie flush as an extension of said playing surface or adapted to be locked in an angularly disposed position with respect to said level playing surface and with respect to said inclined surface, for obstructing the travel of a ball when desired for directing said ball toward certain sections of said playing surface.

JOSEPH J. WARREN. 10
